BELT FASTENER

Filed Oct. 22, 1949

FIG. 1.

FIG. 2.

INVENTOR

WILLIAM WEST.
BY Norman St. Landon

ATTORNEY

UNITED STATES PATENT OFFICE

165,621

BELT FASTENER

William West, Montreal, Quebec, Canada, assignor to Personal Products Corporation, a corporation of New Jersey

Application October 22, 1949, Serial No. 5,662

Term of patent 14 years

(Cl. D17—3)

To all whom it may concern:

Be it known that I, William West, a citizen of the United States, residing at Montreal, in the Province of Quebec, the Dominion of Canada, have invented a new, original, and ornamental Design for a Belt Fastener, of which the following is a specification, reference being had to the accompanying drawing, forming a part thereof in which:

Fig. 1 is a front elevation of a belt fastener showing my new design; and

Fig. 2 is a side elevation thereof.

I claim:

The ornamental design for a belt fastener, substantially as shown.

WILLIAM WEST.
